DESIGN FOR A DISPLAY PACKAGE FOR STATIONERY OR THE LIKE

Evelyn von Hartmann, Westwood, N. J., assignor to Novelart Manufacturing Company, Long Island City, N. Y., a firm composed of Milton
Kahn and Morris Berg

Application March 22, 1944, Serial No. 113,006

Term of patent 3½ years

(Cl. D80—5)

To all whom it may concern:

Be it known that I, Evelyn von Hartmann, a citizen of the United States, residing at Westwood, in the county of Bergen and State of New Jersey, have invented a new, original, and ornamental Design for a Display Package for Stationery or the like, of which the following is a specification, reference being had to the accompanying drawing, forming a part thereof.

The figure is a perspective view of a display package for stationery or the like, showing my new design.

I claim:

The ornamental design for a display package for stationery or the like, substantially as shown.

EVELYN VON HARTMANN.
